UNITED STATES PATENT OFFICE.

JASON BOTNAR, OF MINNEAPOLIS, MINNESOTA.

STITCH-REMOVING DEVICE.

1,412,836.

Specification of Letters Patent. Patented Apr. 18, 1922.

Application filed March 25, 1921. Serial No. 455,552.

To all whom it may concern:

Be it known that I, JASON BOTNAR, a citizen of the United States, residing at Minneapolis, in the county of Hennepin and State 5 of Minnesota, have invented certain new and useful Improvements in Stitch-Removing Devices; and I do hereby declare the following to be a full, clear, and exact description of the invention, such as will enable others 10 skilled in the art to which it appertains to make and use the same.

My invention relates to improvements in shoe repairing machinery and has for its object to provide an extremely simple and 15 highly efficient device for removing or pulling stitches from shoe welts, after the stitches which connect the soles thereto have been cut, in preparing shoes to be half soled. It is now customary to remove these stitches by 20 hand, which is a very slow and tedious work.

To the above end, generally stated, the invention consists of the novel devices and combinations of devices hereinafter described and defined in the claims.

25 In the accompanying drawings, which illustrate the invention, like characters indicate like parts throughout the several views.

Referring to the drawings:

Fig. 1 is an inner face view of the invention;

30 Fig. 2 is an elevation with a portion of a shoe diagrammatically illustrated by means of broken lines and positioned against one of the stitch removing devices to remove the 35 stitches from the welt thereof; and

Fig. 3 is a fragmentary detail view, in section, taken on the line 3-3 of Fig. 1, also diagrammatically showing a shoe as in Fig. 2.

40 The numeral 4 indicates a revoluble shaft which may be assumed to be mounted on a shoe finishing machine. Mounted on the shaft 4 are two axially spaced wheels 5 and 6 in which the invention is embodied and 45 which wheels are alike, with the exception that the former is of relatively large diameter and provided with dull teeth 7, and the latter of said wheels is of relatively smaller diameter and provided with sharp 50 teeth 8, for a purpose that will presently appear. On the inner face of each wheel 5 and 6, is a hub 9 having a peripheral groove 55 to receive a belt, not shown, provided it is desirable to drive said wheels at a different speed from that of the shaft 4. When the wheels 5 and 6 are driven at the same

speed as the shaft 4, they may be secured for rotation therewith, by set screws, not shown.

The peripheries of the wheels 5 and 6 are 60 beveled toward the inner face thereof and the teeth 7 and 8 are formed thereon, and extend oblique to lines radiating from the axis of said wheels. Preferably, the teeth 7 and 8, at their outer portions, are formed 65 on a relatively flat bevel 11 and their inner portions thereof, are formed on a relatively steep bevel 12, as best shown in Fig. 3. It will be noted that the outer and inner peripheral edges of the wheels 5 and 6 are 70 rounded at 13 and 14, respectively, and that the beveled portions 12 of the teeth 5 and 6 are blended into the rounded edges 13. It will also be noted that the teeth 7 and 8 are made progressively deeper from the outer 75 toward the inner faces, as shown in Fig. 3.

In the use of the invention, the stitches Z, which secure the sole of the shoe Y to the welt thereof, are first cut therebetween, and thereafter, the shoe is held so that the teeth 80 7 of the wheel 5 engage the transverse portions of the cut stitches Z at the outer face of the welt. The stitches Z are first engaged by the beveled portions 11 of the teeth 7, which are at the shallowest portions of said 85 teeth, and thereafter, are engaged by the beveled portions 12 of said teeth, and pulled. The pulled stitches are discharged through the deepest portions of the teeth 7 which are at the outer face of the wheel 5. In case 90 the dull teeth 7 will not pull the stitches, the shoe is shifted to the wheel 6 and the stitches cut flush with the outer face of the welt by the sharp teeth 8 thereof. The rounded edges 13 of the wheels 5 and 6 will 95 not cut or damage the upper of a shoe in case said shoe is moved into contact with the revolving wheel. By the use of this invention, stitches may be very quickly removed from the welt of shoes, either by pulling or 100 cutting the same.

What I claim is:

1. A device of the kind described comprising a revoluble wheel having on its periphery circumferentially spaced stitch removing 105 teeth that are oblique to lines that radiate from the axis of the wheel, said teeth being arranged to be revolved in respect to a shoe welt and operative to remove the stitches which connect the welt to the sole after said 110 stitches have previously been cut.

2. A device of the kind described compris-

ing a revoluble wheel having on its periphery circumferentially spaced stitch removing teeth that are oblique to lines that radiate from the axis of the wheel and are 5 dull, said teeth being arranged to be revolved in respect to a shoe welt and operative to remove the stitches which connect the welt to the sole after said stitches have previously been cut.

10 3. A device of the kind described comprising a revoluble wheel having a beveled periphery and circumferentially spaced stitch removing teeth on said periphery, said teeth being arranged to be revolved in respect to 15 a shoe welt and operative to remove the stitches which connect the welt to the sole after said stitches have previously been cut.

4. A device of the kind described comprising a revoluble wheel having a beveled periphery and circumferentially spaced stitch removing teeth on said periphery, said teeth being progressively deeper toward the inner 20 face of the wheel.

5. A device of the kind described comprising a revoluble wheel having a beveled periphery and circumferentially spaced stitch removing teeth on said periphery, the outer 25 peripheral edge of the wheel being rounded into said teeth, said teeth being arranged to be revolved in respect to a shoe welt and operative to remove the stitches which connect the welt to the sole after said stitches have previously been cut.

6. A device of the kind described comprising a revoluble wheel having a beveled periphery and circumferentially spaced stitch removing teeth on said periphery, the outer 30 peripheral edge of the wheel being rounded into the teeth and said teeth being blended 35 into said rounded edge of the wheel, said teeth being arranged to be revolved in respect to a shoe welt and operative to remove the stitches which connect the welt to 40

the sole after said stitches have previously been cut.

7. A device of the kind described comprising a revoluble wheel having circumferentially spaced stitch removing teeth that are oblique to lines that radiate from the axis of the wheel, the inner portion of said teeth 50 being on a relatively flat bevel and the outer portions of said teeth being on a relatively steep bevel.

8. A device of the kind described comprising a revoluble wheel having circumferentially spaced stitch removing teeth that are oblique to lines that radiate from the axis of the wheel, the inner portion of said teeth being on a relatively flat bevel and the outer portions of said teeth being on a relatively 60 steep bevel, the inner peripheral edge of the wheel being rounded into said teeth.

9. A device of the kind described comprising a revoluble wheel having a beveled periphery and circumferentially spaced stitch 65 pulling teeth on said periphery, said teeth being oblique to lines that radiate from the axis of the wheel, the outer peripheral edge of the wheel being rounded into said teeth and said teeth being blended into said rounded 70 peripheral edge of the wheel, said teeth being arranged to be revolved in respect to a shoe welt and operative to remove the stitches which connect the welt to the sole after said stitches have previously been cut.

10. A device of the kind described comprising a revoluble wheel having on its periphery circumferentially spaced stitch-removing teeth arranged to be revolved in respect to a shoe welt and operative to remove 80 the stitches which connect the welt to the sole after said stitches have previously been cut.

In testimony whereof I affix my signature.

JASON BOTNAR.
